US0D1096605S

(12) **United States Design Patent** (10) Patent No.: **US D1,096,605 S**
(45) Date of Patent: ** Oct. 7, 2025

(54) **SOLAR HEAT COLLECTOR**

- (71) Applicant: **JOSKE'S DE MEXICO S.A. DE C.V.**, Coyoacán (MX)
- (72) Inventor: **Jacobo Zyman Reinisch**, Huixquilucan (MX)
- (**) Term: **15 Years**
- (21) Appl. No.: **35/522,569**
- (22) Filed: **Sep. 5, 2024**

(80) **Hague Agreement Data**

Int. Filing Date: **Sep. 5, 2024**

Int. Reg. No.: **DM/240686**

Int. Reg. Date: **Sep. 5, 2024**

Int. Reg. Pub. Date: **Oct. 11, 2024**

(51) **LOC (15) Cl.** 13-02

(52) **U.S. Cl.**

USPC **D13/102**

(58) **Field of Classification Search**

USPC D13/102, 101, 103, 107, 108, 110, 199

CPC H01L 31/18; H01L 31/022433; H01L 31/0224; H01L 31/0475; H01L 31/042; H02S 10/40; Y02E 10/50

See application file for complete search history.
